(57) **CLAIM**

The ornamental design for a beach tote bag with a mesh bottom, as shown and described.

DESCRIPTION

FIG. 1 is a top perspective view of a beach tote bag with a mesh bottom showing my new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is bottom perspective view thereof.

The evenly spaced dashed lines in the drawings depict stitching and are included in the claimed design. The unevenly spaced dashed line in the drawings with varying length are not included in the claimed design.

1 Claim, 8 Drawing Sheets(56)
